ROTOR

Filed May 15, 1926

UNITED STATES PATENT OFFICE

FRED E. DUMBLETON, OF MILWAUKEE, WISCONSIN, ASSIGNOR TO ALLIS-CHALMERS
MANUFACTURING COMPANY, OF MILWAUKEE, WISCONSIN, A CORPORATION OF
DELAWARE

ROTOR

Application filed May 15, 1926. Serial No. 109,247.

This invention relates generally to improvements in rotors, and relates more specifically to improvements in the construction and operation of mechanism for adjusting 5 the vanes of the rotors of various types of rotary machines such as turbines, pumps or propellers.

An object of the invention is to provide a new and useful rotor which is simple in construction and efficient in operation. Another 10 object of the invention is to provide improved mechanism for controlling the operation of rotary machines by adjustment of the vanes of the rotors thereof. A further object of the 15 invention is to provide simple and efficient means for effecting angular adjustment about their longitudinal axes of the vanes of various types of rotors. These and other objects and 20 advantages will appear from the following description.

Some of the novel features of rotor vane 25 adjusting mechanism, shown but not specifically claimed herein, form the subject of co-pending applications Serial No. 40,136 filed June 29, 1925, now Patent 1,656,017 issued Jan. 10, 1928, and 43,167 filed July 13, 1925.

A clear conception of an embodiment of the present invention and of the operation of devices constructed in accordance therewith, 30 may be had by referring to the drawing accompanying and forming a part of this specification in which like reference characters designate the same or similar parts in the various views.

Fig. 1 is an enlarged fragmentary central 35 vertical section through an axial flow hydraulic turbine rotor and a portion of the main shaft thereof.

Fig. 2 is a transverse horizontal section 40 through the shaft of the hydraulic turbine, the section being taken between the hollow and solid shaft portions.

Fig. 3 is a fragmentary central vertical 45 section through a portion of the vane adjusting mechanism of the hydraulic turbine shaft disclosed in Fig. 1, the section being taken at right angles to the plane of section of Fig. 1.

Fig. 4 is a central vertical section through 50 a vertical hydraulic turbine installation em-

bodying an axial flow rotor having adjustable vanes.

While the invention has been shown and described herein as being specifically applied to an axial flow hydraulic turbine, it will be 55 apparent that most of the features of the improvement are more generally applicable to the rotors of various types of machines such as fluid actuated turbines, fluid pumps or conveyance propellers. The hydraulic turbine unit specifically illustrated in the drawing comprises in general a rotor 2 having a plurality of pivotally supported vanes 3 radiating from a one-piece central hub 4 which is secured to the bottom flange 29 of the hollow 60 lower section 5 of a main shaft; a main turbine casing 6 cooperating with adjustable inlet guide vanes 7 to form a housing for the rotor 2, and providing a vane free transition 65 space 8 for conducting water from a penstock 11 past the guide vanes 7 toward the rotor 2 in the form of a vortex advancing in an axial direction; a draft tube 12 for conducting the water delivered from the rotor 2 to the tail-race 13; an electric generator or 70 other energy translating device 10 associated with the upper solid section 9 of the main shaft; and a suitable foundation 14 for supporting the turbine and the energy translating device 10 associated therewith.

Referring specifically to Fig. 1, the dovetail shaped radiating vanes 3 of the rotor 2 which may be two or more in number, are pivotally associated with the one-piece hub 4 comprising an outer annular shell and an 85 inner supporting portion 19 cast integral with the outer shell. The outer shell portion of the hub 4 is provided with radial bores 21 which fit external cylindrical surfaces of the vanes 3, and the central supporting portion of the hub 4 is provided with radial projections having cylindrical outer surfaces 20 formed concentric with the bores 21 and fitting recesses in the ends of the vanes 3, thereby providing two 90 remotely spaced bearings for each vane 2. The bores 21 are of considerably larger diameter than the cylindrical surfaces 20 and the hub end of each vane 3 is provided with an integral bevel gear segment 18 extending upwardly from the axis of rotation of the vane 95 100

into the hub 4. Each vane 2 is also provided with an opening normally closed by a plug 25, this opening communicating with a chamber within the hub of the vane, and being of sufficient diameter to permit insertion and removal of a retaining pin 24 which is screw threaded into the central hub portion 19 and has an outer flange coacting with a surface of the vane 3 to prevent outward displacement thereof. The retaining pins 24 are capable of being locked in adjusted position by means of locking screws 26 and lock nuts 27, and the lower portion of the hub 4 is provided with a removable closure cap 28 bolted thereto, for normally enclosing the screws 26 and the nuts 27.

The hub 4 is detachably secured to the bottom flange 29 of the lower hollow shaft section 5 by means of stud bolts 30, and has its upper portion provided with an opening which is normally closed by the flange 29. Located centrally within the shaft section 5 is a vane adjusting shaft 16, the lower end of which carries a bevel gear 17 which meshes with the bevel gear segments 18 of all of the vanes 3. The gear 17 is fixed to the shaft 16 by means of a clamping nut 23, and the lower extremity of the shaft 16 is mounted in a guide bearing 22 formed in the central hub portion 19. A worm wheel 34 attached to the upper extremity of the shaft 16 by means of a clamping nut 35, meshes with an adjusting worm 37 carried by a transverse adjusting shaft supported in a gear casing comprising lower and upper sections 31, 32 respectively. The gear casing is mounted upon the adjusting shaft 16 and is located between a lower flange on the upper shaft section 9 and an upper flange on the lower shaft section 5, these flanges coacting with an enclosing ring 15 which also serves to unite the shaft sections. The gear casing comprising the sections 31, 32 has a lateral projection fitting within a retaining recess 41 in order to prevent rotation of the gear casing relatively to the ring 15, and is adjustably associated with the upper flange of the shaft section 5 by means of jack screws 33. The depending ends of the jack screws 33 are protected by means of a casing 36 secured to the shaft section 5. An indicator comprising a lever 38 and a pointer 39 cooperating with a dial 40 is located between and is carried by the gear casing sections 31, 32 for the purpose of indicating the position of adjustment of the rotor vanes. The shaft of the worm wheel 37 which is likewise carried by the gear casing sections 31, 32 is provided with a locking device 42 as shown in Fig. 2.

During normal operation of the hydraulic turbine unit, the guide vanes 7 are properly adjusted to admit water from the penstock 11 through the transition space 8 to the rotor 2 in the form of a vortex advancing axially past the rotor vanes 3 to the draft tube 12. While passing through the rotor 2, a portion of the

energy of the water is converted into rotary motion of the rotor 2 which is transmitted through the shaft sections 5, 9 to the energy translating device 10 in a well known manner. While the unit is thus operating normally, the vanes 3 are locked in position by the worm 37 and worm wheel 34 and by the jack screws 33 which are set to exert a downward pressure upon the bevel gear 17 through the casing sections 31, 32, the worm wheel 34 and the adjusting shaft 16, thus wedging the gear 17 against the gear segments 18.

If it is desired to angularly adjust the rotor vanes 3 about their pivotal axes, the unit may be shut down by closing the guide vanes 7, whereupon the jack screws 33 may be manipulated to release the lock afforded by the downward wedging action of the gear 17, and the locking device 42 may be released to free the worm 37. By manipulating the released worm 37, the worm wheel 34, the adjusting shaft 16 and the gear 17 may be rotated relatively to the shaft section 5 thus simultaneously rotating the vanes 3 about their pivotal axes. As the worm 34 rotates, the indicating pointer 39 is moved along the dial 40 until the desired degree of adjustment has been attained, whereupon the vanes 3 may again be locked in adjusted position by means of the jack screws 33 and the locking device 42.

The one-piece construction of the hub 4 and the provision of remotely spaced internal and external bearing surfaces 20, 21 for each vane 3, provides a rigid and compact rotor structure. When assembling the rotor 2, the closure plugs 25 of the vanes 3 are removed and the gear segments 18 are first slipped through the openings bounded by the bearing surfaces 21, after which the vanes may be positioned to properly coact with the surfaces 20, 21. The retaining pins 24 may then be inserted and locked into properly adjusted position after which the plugs 25 may be caulked, welded or otherwise permanently attached to the vanes. The rotor 2 may be removed from the shaft section 5 at any time by merely releasing the stud bolts 30 and dropping the rotor away from the gear 17 and shaft end 22. The vane adjusting mechanism is however accessible without dismantling the rotor 2, by virtue of the location of the adjusting mechanism between the shaft sections 5, 9 and above the normal water level.

It should be understood that it is not desired to limit the invention to the exact details of construction and operation herein shown and described, for various modifications within the scope of the claims may occur to persons skilled in the art.

It is claimed and desired to secure by Letters Patent:

1. In combination, a hollow main shaft, a hub associated with said shaft, a plurality of vanes pivotally supported by said hub, a gear segment associated with each of said vanes

5 adjacent to its pivot, an adjusting shaft located within said main shaft and extending into said hub, a gear connecting said adjusting shaft and said gear segments, said gear being disposed at the side of said hub adjacent to said hollow shaft, and means for axially shifting said adjusting shaft gear to lock said vanes in adjusted position.

2. In combination, a hollow main shaft, a hub secured to said shaft, a plurality of vanes 10 pivotally supported by said hub, a bevel gear segment formed integral with each of said vanes adjacent to its pivot, an adjusting shaft located within said main shaft and extending 15 into said hub, a bevel pinion secured to said adjusting shaft, said pinion being disposed at the side of said hub adjacent to said main shaft and coacting with all of said gear segments, and means for axially moving said adjusting shaft gear to lock said gear segments 20 in adjusted position.

3. In combination, a hollow main shaft, a hub secured to said shaft, said hub comprising a shell portion and a central portion 25 formed integral with said shell portion, a plurality of vanes pivotally supported by both said shell and central hub portions, an adjusting shaft located within said main shaft and having its lower extremity slidably journaled in said central hub portion and associated with said shaft above the lower journal thereof, gearing disposed within said shell portion for transmitting motion from said adjusting shaft to said vanes, and means 35 for axially shifting said adjusting shaft to lock said gearing in adjusted position.

4. In combination, a main shaft, a hub secured to said shaft, said hub comprising an outer portion and an inner portion formed 40 integral with said outer portion, a plurality of vanes pivotally associated with said hub and each having outer and interior cylindrical surfaces coacting with internal and external cylindrical surfaces of said outer and inner hub portions respectively, and retaining screws secured to said inner hub portion and coacting with surfaces of said vanes for preventing outward displacement of said vanes.

5. In combination, a main shaft, a hub secured to said shaft, said hub comprising an outer portion and an inner portion formed integral with said outer portion, a plurality of vanes pivotally associated with said integral hub portions only and extending outwardly 55 beyond said outer hub portion, means for preventing outward displacement of each of said vanes, a gear segment formed integral with each of said vanes, an adjusting shaft having its lower extremity slidably journaled in said central hub portion, a gear secured to said adjusting shaft above the lower journaled extremity thereof and meshing with all of said gear segments, and means for axially shifting said adjusting shaft to lock said 60 gearing in adjusted position.

6. In combination, a main shaft, a hub secured to said shaft, said hub comprising outer and inner portions, a plurality of vanes pivotally associated with said inner hub portion and extending outwardly beyond said outer hub portion, each of said vanes having a pocket provided with an opening adjacent to its pivotal axis, and retaining screws insertable through said openings of said vanes and cooperating with said inner hub portion to prevent outward displacement of said vanes, said screws being normally sealed within said pockets. 70

7. In combination, a main shaft having a bore, a hub associated with said shaft, a plurality of vanes pivotally associated with said hub, and means for adjusting said vanes about their pivotal axes, said means comprising an adjusting shaft, a gear enclosing casing mounted within said main shaft bore, means for preventing rotation of said enclosing casing relatively to said main shaft, and gearing connecting said casing and said adjusting shaft. 80

8. In combination, a hollow main shaft having a bore, a hub secured to said shaft, a plurality of vanes pivotally associated with said hub, an adjusting shaft located within said main shaft, gearing connecting said adjusting shaft and said vanes, a gear enclosing casing having a portion fitting said bore and being associated with an end of said adjusting shaft, means for preventing relative rotation of said enclosing casing and said main shaft, and worm gearing connecting said casing and said adjusting shaft. 90

9. In combination, a main shaft, a hub secured to said shaft, said hub comprising outer and inner portions separated by an annular space, a plurality of vanes pivotally associated with said inner hub portion and extending across said space and outwardly beyond said outer hub portion, each of said vanes having a pocket provided with an opening adjacent to its pivotal axis, a retaining screw insertable into said pockets through each of said openings and cooperating with said inner hub portion to prevent outward displacement of the corresponding vane, and means within said space for moving said vanes about their pivotal axes. 105

10. In combination, a main shaft, a hub secured to said shaft, a plurality of vanes pivotally associated with said hub, each of said vanes having a pocket provided with an opening adjacent to its pivotal axis, and retaining screws insertable into said pockets through said openings and cooperating with said hub to prevent outward displacement of said vanes. 120

11. In combination, a main shaft, a hub secured to said shaft, a plurality of vanes pivotally associated with said hub, each of said vanes having a pocket provided with an opening adjacent to its pivotal axis, a retaining 130

screw insertible into each of said pockets through each of said openings and cooperating with said hub to prevent outward displacement of the corresponding vane, and a 5 closure plate for each pocket associated with each of said openings for inclosing said screws.

12. In combination, a main shaft, a hub secured to said shaft, a plurality of vanes 10 pivotally associated with said hub, each of said vanes having a pocket provided with an opening adjacent to its pivotal axis, means insertible into said pockets through said openings and cooperable with said hub to prevent 15 outward displacement of said vanes, and a closure plate for each of said pocket openings.

13. In combination, a main shaft, a hub secured to said shaft, a plurality of vanes 20 pivotally associated with said hub, each of said vanes having a pocket disposed entirely within the contour of said hub and provided with an external opening, retaining screws insertible into said pockets through said openings and cooperable with said hub to prevent 25 outward displacement of said vanes, and a closure plate for each of said openings disposed flush with the external surface of said hub.

14. In combination, a main shaft, a hub 30 secured to said shaft, a plurality of vanes pivotally associated with said hub, each of said vanes having a pocket disposed within the outer surface of said hub and adjacent to the pivotal axis of the vane, means insertible into 35 said pockets and cooperable with said hub to prevent outward displacement of said vanes, and a detachable plate for permitting access to each of said pockets, said plates being disposed flush with the outer surface of said hub.

40 In testimony whereof, the signature of the inventor is affixed hereto.

FRED E. DUMBLETON.
